L. E. WATERMAN.

LANDING DEVICE.

APPLICATION FILED JULY 10, 1916.

1,225,897.

Patented May 15, 1917.

Fig. 3.

UNITED STATES PATENT OFFICE.

LEWIS E. WATERMAN, OF ROCKFORD, ILLINOIS, ASSIGNOR TO EMERSON-BRANTINGHAM COMPANY, OF ROCKFORD, ILLINOIS, A CORPORATION OF ILLINOIS.

LANDING DEVICE.

1,225,897.

Specification of Letters Patent. Patented May 15, 1917.

Application filed July 10, 1916. Serial No. 103,459.

To all whom it may concern:

Be it known that I, LEWIS E. WATERMAN, a citizen of the United States, residing at Rockford, in the county of Winnebago and State of Illinois, have invented certain new and useful Improvements in Landing Devices, of which the following is a specification.

This invention relates to landing devices employed with farming implements, and especially in connection with sulky plows for adjusting the draft means laterally relatively to the frame to cause the plow to take more or less land.

The primary object of my invention is to provide a simple and improved landing device which will be easy to manipulate and control and will effectively serve the purpose for which it is designed. I have also aimed to provide a landing device adapted to be controlled by a pair of foot levers which may be depressed to release the device from locked position in which the draft means are held against lateral movement and may be moved forwardly and backwardly with the levers held depressed for swinging the draft means laterally.

A further object is to provide an improved landing device and draft means whereby the draft tongue may be adjusted from a central position on the frame to a laterally offset position and vice versa, without disturbing the landing device or any of the parts connected therewith.

Referring to the drawing,—

Figure 1 is a plan view of my improved landing device in connection with a frame structure;

Fig. 2 is a vertical sectional view longitudinally of the landing device; and

Fig. 3 is a front view of the landing device with a portion shown in section.

Landing devices of the character to which my improvements relate are generally mounted on the fore part of a plow frame and connected with the draft means for the purpose of moving the same laterally with respect to the frame to change the line of draft. Such devices are preferably foot-operated so that the driver may conveniently change the line of draft to cause the plow to take more or less land whenever desired without interfering with handling the reins of the horses or otherwise employing his hands in operating the plow. It should be

understood, however, that my improved device so far as its function of adjusting a draft means laterally with respect to a frame is concerned, may be employed in connection with any implement or vehicle in which it is desired to so adjust the draft means.

In the present instance, I have shown but a portion of a frame comprising vertically spaced transverse angle and channel bars 4 and 5 respectively, the bar 5 having rigidly secured thereto a central rearwardly extending frame portion 6. A swinging frame designated generally by reference character 7 is provided for carrying a draft tongue or pole 8 in either a central position or a laterally offset position so as to accommodate the draft means for either a two or three horse hitch. This swinging frame interposed between the bars 4 and 5 and pivotally mounted at 9 on the frame portion 6 may be of suitable construction so that the pole 8 may be bolted thereto in either the central position in which it is shown in full lines in Fig. 1 or the laterally spaced position indicated by 11 in dotted lines. This frame may consist of a pair of bars 12 and 13 bolted together forming a substantially parallelogram frame, one corner of which is pivoted at 9 to the main frame and the sides 14 and 15 of which extend substantially parallel with the line of draft and to which the tongue is adapted to be bolted as indicated. It will be obvious that when the tongue is bolted to the swinging frame at either side thereof, it may be swung laterally with the swinging frame on the pivot axis 9 of said frame.

My improved landing device employed for swinging the tongue-carrying frame laterally and holding the same locked in set position is carried by a bracket designated generally by 16 bolted at 17 to the cross bar 4 of the main frame. This bracket projects forwardly from its mounting on the frame and is shaped to provide at its forward end an apertured bearing sleeve 18 on an upright axis and arcuate ratchet faces 19 arranged concentric with the bearing 18 on opposite sides thereof and on the under side of the bracket. A pair of foot levers 21 which serve also as stirrups are pivotally mounted at 22 on a bracket 23 suitably mounted on the bearing sleeve 18. A bolt 24 passing through the aperture of said

sleeve 18 holds the bracket 23 in position. The foot levers are provided intermediate their ends with toothed faces 25 adapted to engage the ratchet faces 19 and are constantly urged into engagement with said faces by expansion springs 26 interposed between the levers and outer extensions 27 of the bracket 23. This bracket also carries an integral forwardly projecting arm 28 which is pivotally connected to the front end of the frame 12 through the intermediary of a link 29.

By reason of this construction the tongue is normally locked in connection with the main frame, and when it is desired to angle the tongue with respect to the frame, that is, swing the tongue laterally on the pivot 9, the operator will depress the foot levers 21, releasing the same from engagement with the ratchet faces 19. Still holding the levers depressed the operator will rock the levers about the pivot bolt 24 by forward pressure on the lever opposite the side to which he wishes to swing the tongue. That is, viewing Fig. 1, if it is desired to swing the tongue to the left, the right hand lever 21 will be pressed forwardly. When the line of draft has been changed to the desired extent, the downward pressure on the levers is released whereupon the levers will be moved into locking engagement with the ratchet faces 19 by the action of the springs 26.

By employing springs of different tension, the principle of operation may be slightly changed. During operation the driver generally rests his feet on the stirrups or levers 12 and in the instance that the springs 26 are not of sufficient strength to hold the levers in uppermost position against this downward pressure on the levers, the same will be held out of locking engagement. This does not disturb the operation of the plow, since the driver, having his feet on the stirrups, has constant control of the line of draft. He may maintain the draft straight ahead without any effort, since the levers 21 are diametrically oppositely disposed and are in the position of ordinary foot stirrups. Under this condition, the device may be set in a locked position by simply removing the downward

pressure from the levers, that is, by the operator withdrawing his feet therefrom. The springs may, however, be of sufficient strength to hold the levers in locked position against the normal weight of an operator's feet on the levers so that when it is desired to change the line of draft, it will be necessary for the operator to forcibly depress the levers and swing the same in a backward and forward movement in their depressed position to effect the desired adjustment.

I claim:—

1. A landing device comprising a frame, a tongue connected with the frame so as to swing laterally relatively thereto, means for swinging the tongue laterally and holding it locked against such movement comprising a pair of opposed foot levers movable about a common pivot to effect said swinging movement, and means for locking the foot levers in set position to lock the tongue against said swinging movement, said foot levers and locking means being arranged so that the levers must be vertically depressed to release them from locking position and then swung backwardly and forwardly in a horizontal plane to swing the tongue laterally.

2. A landing device comprising a frame, a draft element pivotally mounted thereon to swing laterally relatively to the frame, a bracket fixed to the frame, an element pivotally mounted on said bracket on an upright axis, a connection between said element and the draft element so that the two will swing in unison, a pair of foot levers pivotally mounted on said element on horizontal axes and extending in opposite directions from the pivot axis of said element, a ratchet connection between each lever and the bracket arranged so that the levers will be disengaged from the bracket upon being swung downwardly upon their pivots, and spring means urging the levers into engagement with the brackets, whereby to swing the draft element the levers must be first depressed to disengage from the ratchet faces and then swung forwardly and rearwardly on the upright axis of said element.

LEWIS E. WATERMAN.
